THREAD GUIDE ROLLER

It is a common practice to conduct a thread or yarn with several windings over a thread guide roller, especially in combination with a draw godet where the windings pass around both the godet and guide roller, e.g. as the so-called draw or stretch rolls of drawing apparatus. The individual thread windings are spatially separated along the contacting surfaces of the godet and guide roller, this separation being achieved in a known manner by the slight tilting of the axes of the godet and guide roller. Thus, the godet is normally positioned adjacent the guide roller with almost parallel axes of rotation which form a very small angle sufficient to produce the desired effect. One attempts to maintain this spatial separation because it is essential to avoid thread windings running over one another and a resulting damage or breakage of the threads.

If the thread or yarn which runs over the guide roller is one which extends directly from this roller to a previous or subsequent thread twisting device, the path of travel or run of the thread on the guide roller is extremely uneven. This arises from the fact that a twist being formed either as a true twist or as a false twist is transmitted from the twisting device along the thread itself up to the guide roller where this twist causes the thread to roll in the direction of twist along the surface of the roller. This movement of the thread axially of the guide roller causes it to come into contact with adjacent windings or loops around the guide roller and even climb over these adjacent windings so as to cause frequent damage to the filaments or breakage of the thread. Such unsatisfactory results can be observed in draw-twist apparatus whether one is producing a true twist with a so-called ring twister accompanied by the formation of a thread balloon or whether one is producing a false twist with a small twisting tube or other conventional false twist device.

One object of the present invention is to provide a thread guide roller which will prevent this rolling movement of threads axially of the roller under the influence of a twist imparted to the running thread just before or after its winding or looping contact with the roller, especially in draw-twist apparatus which requires at least one such guide roller in combination with a godet as thread drawing means. Another object of the invention is to provide a variation in the construction of this thread guide roller which will solve the stated problem and which can be readily adapted to existing guide rollers. Other objects and advantages of the invention will become more apparent from the following detailed disclosure.

It has now been found, in accordance with the invention, that a substantial improvement can be achieved in avoiding thread damage during such conventional thread processing by providing a thread guide roller comprising a rotatably mountable thread-receiving cylindrical roller having a circumferential bead projecting radially outwardly from its cylindrical surface adjacent the ends thereof. This roller is especially effective in draw-twist apparatus where it is employed in combination with a godet as one element in thread drawing means, such apparatus also including thread twisting means in direct threaded connection with the guide roller such that the imparted twist is transmitted along the thread from the twisting means to the guide

roller. With several windings transported along the surface of the guide roller, the bead is situated between the thread run-off end of the roller and the next adjacent thread winding, i.e. between the last two windings near one end of the roller, preferably at a distance from the end of the thread contacting surface of about 15 to 40 percent of the length of this normally cylindrical surface.

Specific embodiments of the invention are described in greater detail hereinafter in conjunction with the accompanying drawings in which:

FIG. 1 is a partly schematic illustration of draw-twist apparatus, including a side elevational view of a godet and the thread guide roller of the invention;

FIG. 2 is a front elevational view of the godet and thread guide roller of FIG. 1, another preferred arrangement of the guide roller in reference to the godet being shown in broken lines; and

FIGS. 3-8 are cross-sectional views of a number of preferred embodiments of the thread guide roller of the invention.

Referring first to FIGS. 1 and 2, a conventional rotatably driven godet 1 on axis 1a is positioned adjacent to the thread guide roller 2 which is freely turnable on its axis 2a and which is provided with the circumferential bead 3 spaced inwardly from its front or right end by a distance of about 25 percent of its length. The thread 4 extends downwardly from any suitable thread feeding means, for example a pair of feed rolls which may also be a godet and guide roller, to first contact the thread guide roller 2 located laterally above the godet 1. The thread 4 then loops or winds several times around both the godet 1 and roller 2, a number of these individual windings 5 lying to the left of the bead 3 while the last winding 6 lies to the right of this bead 3 as the thread 4 is taken off the guide roller 2 and conducted directly to a thread twisting means where an S-twist is imparted to the thread.

The S-twist imparted by the twisting device travels back to the roller 2 and causes the winding 6 to roll to the left in an axial direction along the circumferential surface of the roller, such that the winding 6 would normally roll over the windings 5. However, the bead 3 prevents this rolling movement, the thread winding 6 remaining in contact with the right flank of the bead 3 without climbing over this bead. In this manner, i.e. with the bead acting as a barrier or obstacle to the rolling effect of the twisted thread, damages to the thread and breaking of the thread can be completely avoided.

This first arrangement is also shown in FIG. 2 in solid lines as a front view of the godet and guide roller of FIG. 1, i.e. where the guide roller or run-off roller 2 is positioned laterally above the godet 1. The guide roller 2' is however preferably placed laterally below the godet 1 (as shown in broken lines), especially where these two members serve as the draw rolls in the draw-twist apparatus with a generally vertical path of travel of the yarn or thread 4'. In this latter case, the highly tensioned thread 4' as it is transported approximately vertically downwardly from a feed godet or similar feed means runs laterally in close proximity to the draw godet 1 without touching this godet and then first contacts the guide roller 2' which is approximately tangent to the vertical path of thread travel. Thereafter, the

thread is wound in running contact several times around both the godet 1 and roller 2' to form a number of spaced loops in the same manner as shown in FIG. 1. Again, the last winding 6 is to the right of the bead 3' and runs off from this position, again in an approximately vertical path to the thread twisting means.

The bead 3' on guide roller 2' as shown in FIG. 2 also prevents the rolling movement of the last winding over the remaining windings 5 just as in the embodiment of FIG. 1. It is further important, however, to avoid thread damages which can be caused by the fact that the godet may capture, wind up and tear off threads or individual filaments thereof which are received as they run past the godet in a relatively weakly tensioned or gripped condition. This additional source of thread damage is substantially avoided if the godet is positioned to one side, i.e. laterally with reference to the thread path, either above or below the guide roller so as to be in the vicinity of or in close proximity to that free end or thread length extending from the guide roller which is under the greatest tension.

Thus, where the most strongly tensioned thread lies above the guide roller 2' as shown by broken lines in FIG. 2, i.e. where the thread is being drawn or stretched, it is advisable to position the godet 1 laterally above this roller 2' and close to the upper more strongly tensioned thread 4' as it comes onto the guide roller. Viewed in terms of the approximately vertical path of the thread 4', the thread length under higher tension passes downwardly close by to the godet 1 and past this godet onto the guide roller 2' placed laterally beneath the godet. Then, the thread continues through several loops or windings under essentially slighter tension around both the godet and roller, the last winding being held in place by the bead 3', before it again resumes an approximately vertical direction of travel as it runs off of the roller 2' down to a ring-twist spindle or similar twisting means. This arrangement has the additional effect of providing a maximum surface contact of the thread 4' as it is first brought onto the godet/roller combination, i.e. with reference to its initial contact with the roller 2'. At the same time, the last winding 6 as it runs off the godet/roller combination has a minimum of contact with the cylindrical surface of the guide roller 2' while being maintained axially of this roller by the bead 3'. In this manner, breaking or other damage to the thread is most extensively avoided while ensuring the uniform running and even spacing of the windings on the godet/roller combination without any axial thread rolling movement over long periods of continuous operation.

The individual beads 3 (or 3') can be integral with the guide roller 2 as shown in FIG. 3. However, in order to equip existing thread guide rollers with a supplemental bead as required by the invention, it is possible to construct the bead separately as a ring-shaped member which can then be pressed, shrink-fitted or otherwise drawn or forced onto the existing roller in closely fitting contact with the thread contacting surface of the roller, i.e. as shown by the ring bead 3a in FIG. 5. Such ring-members can also be fixed by adhesives, tensioning or the like, but must extend completely around the circumference of the roller surface.

Another especially preferred embodiment of the thread guide roller is shown in FIGS. 4 and 6 wherein

the particular bead 3b or 3c is integral with a shell or sleeve 7 capable of being slipped onto the roller 2 such that this sleeve provides the thread contacting surface of the guide roller. This sleeve 7 is especially adapted to be removably mounted, e.g. with radial tightening screws or other means of holding it firmly onto the roller 2. However, the annular ring member 3a as shown in FIG. 5 can also be removably mounted, e.g. by screws extending radially through its apex, and can be easily slipped along the roller 2 so as to adapt the roller to any specific operation or different thread run-off configurations requiring one or several windings. This ring member therefore represents an especially economical embodiment of the invention for re-equipping existing guide rollers.

It has been found to be quite satisfactory to employ beads having an approximately triangular cross-section as indicated in FIGS. 3, 4 and 5, especially with a flattened or rounded apex, e.g. as with an approximately trapezoidal cross-section as suggested by FIG. 6. Other shapes are also feasible, depending upon the desired anti-rolling effect to be achieved. In all cases, the flanks on either side of the bead should form an obtuse angle with the thread contacting surface of the roller.

In order to prevent a severe rolling effect in difficulty supported threads having a very strong twist, it is further recommended that the bead be constructed with concave oppositely disposed flanks running smoothly into the thread contacting surface of the cylindrical roller, i.e. substantially as illustrated by the embodiment of FIG. 6. With the gradually increased slope or inclination of the flank facing the last runoff winding, the upward climbing movement of the thread as it is rolled axially by the twist is completely stopped. One can further increase this rounded concave shape of the flank rather than providing a reverse curve over the top of the bead, FIG. 7, respectively the ring bead may even be given a circular or oval cross-section, FIG. 8, thereby avoiding any possibility of the thread riding up over the bead.

The minimum height of the bead, i.e. in its radial direction outwardly from the cylindrical roller surface, can be easily determined for any operation by a few routine tests. This height should ordinarily be at least five times and preferably many more times the diameter of the thread or yarn being transported, again depending upon its precise cross-sectional shape or configuration.

If the bead is installed as a ring member or as part of a sleeve slipped onto the original guide roller, it is possible to construct the bead of a material different from that of the roller, e.g. of a durable plastic material, chromed or mat-chromed V4A-steel or even a ceramic material. Especially good results have been achieved with a bead composed of a wear-resistant plastic while the cylindrical thread contacting roller is composed of a hard surfaced metal or ceramic material. The bead material should be very smooth so that the thread or yarn does not discover a holding position or staircase indentation which would encourage a rolling combing movement.

When employing a simple thread guide roller without several windings along its length, it is possible to locate the bead at about the center of the roller. Depending upon the direction of thread twist, i.e. either an S-twist

or a Z-twist, the singly looped thread can be appropriately positioned with the thread extending to the twisting device located on that side of the bead which will oppose the rolling movement caused by the transmitted torque or twist on the thread. In conventional drawtwist apparatus, however, the thread is wound or looped a number of times around the guide roller and godet acting together as rotatable posts or rolls with the thread looped partly around the guide roller, crossing over the loop partly around the godet, crossing back to the roller and repeating this path several times in a spiral or helical type of winding. Since the godet is normally of larger diameter than the guide roller, larger loops are formed on the godet than the roller as indicated in the drawings, and if desired, the godet may be heated for treatment of the transported thread at an elevated temperature. In this case, the bead is best located about 15 to 40 percent of the length of the guide roller from the run-off end, preferably about 20 to 30 percent from this end.

The multi-looped winding of the godet/roller combination is particularly desirable in a draw-twist apparatus where the thread is first drawn or stretched, i.e. between a first driven godet/roller pair acting as feed rolls and a second driven godet/roller pair acting as the draw rolls, the latter pair of rolls turning at a higher rotational speed than the first set of feed rolls to impart a predetermined stretching to the thread under relatively high tension. Twist is then immediately imparted to the stretched thread after it leaves the draw rolls, it being essential for purposes of the invention to provide a beaded guided roller as described herein as a means of counteracting the rolling movement of the thread along this guide roller of the draw rolls. The twisted thread can then be taken up on a spindle or supply bobbin while substantially avoiding or completely preventing thread breakage and damage to the thread, yarn or individual filaments during the draw-twist operation.

The beaded thread guide roller of the invention is not only successful in counteracting the axially directed rolling movement of a twisted thread along the roller surface but also eliminates any necessity for installing so-called twist stoppers or other complicated devices between the twisting device and the guide roller of the drawing means, such devices being only partly effective in preventing a twist from being carried back to the guide roller. This in turn permits a relatively short span between this guide roller and the twisting device with a corresponding reduction in the overall effective operating length of the draw-twist apparatus in the usually vertical direction of thread travel.

Other similar thread processing operations requiring a thread guide roller to be used with a thread having an applied twist or torque causing the undesired rolling movement may also be substantially improved by employing the beaded roller of the invention, e.g. whether the twist is communicated forwardly along the thread as it is first run on the guide roller or backwardly along the thread as it is run off the last winding on the guide roller. The latter arrangement is much more common in draw-twist apparatus whereas the former arrangement is more likely to be used where the draw rolls receive a twisted thread for heat treatment, e.g. in fixing a thread which has been false twisted on a heated godet.

These and other variations of the overall apparatus will be readily apparent to those skilled in this art since one can employ quite conventional apparatus for different thread treating operations while simply incorporating the essential beaded guide roller of the invention. Accordingly, the invention is not limited to the specific embodiments of apparatus illustrated herein except to the extent designated by the spirit and scope of the accompanying claims.

10 The invention is hereby claimed as follows:

1. In draw-twist apparatus having thread feed means and drawing means including a godet rotatable on its axis in combination with an adjacent thread guide roller which is freely turnable on an axis slightly tilted with reference to the godet axis to receive and advance a tensioned thread in running contact with spatially separated thread windings passing around both said godet and roller and also having thread twisting means 15 to receive and impart a twist to the thread immediately following said drawing means such that twist is transmitted along the thread extending from said twisting means back to said godet and guide roller, the improvement of a thread guide roller positioned as means to receive the thread which is more strongly tensioned directly from said feed means and as means to extend the less strongly tensioned thread directly to said twisting means, said thread guide roller having an elongated cylindrical thread contacting surface of constant radius 20 with a single circumferential bead projecting radially from said surface intermediate the ends thereof to prevent the imparted twist of the less strongly tensioned thread extension from causing a rolling back of the thread axially along the roller.

2. Draw-twist apparatus as claimed in claim 1 wherein said circumferential bead is located on said thread guide roller at a distance from one end thereof of about 15 to 40 percent of the length of said thread 25 contacting surface.

3. Draw-twist apparatus as claimed in claim 1 wherein said circumferential bead is a ring-shaped member constructed separately from said roller and forced onto said roller in closely fitting contact with said thread contacting surface.

4. Draw-twist apparatus as claimed in claim 1 wherein said circumferential bead is located on a cylindrical annular sleeve slipped onto a roller, said sleeve providing a thread contacting surface on each side of 30 said bead.

5. Draw-twist apparatus as claimed in claim 4 wherein said circumferential bead is located at a distance from one end of said sleeve of about 15 to 40 percent of the sleeve length.

6. Draw-twist apparatus as claimed in claim 1 wherein said circumferential bead consists of a wear-resistant plastic material while the remaining thread contacting surface is composed of a hard-surfaced metallic or ceramic material.

7. Draw-twist apparatus as claimed in claim 1 wherein said circumferential bead has an approximately triangular to trapezoidal cross-section with oppositely disposed flanks forming an obtuse angle with the thread contacting surface of the said roller.

8. Draw-twist apparatus as claimed in claim 1 wherein said circumferential bead has a rounded triangular to trapezoidal cross-section with oppositely

disposed flanks providing a smooth rounded concave surface with the thread contacting surface of said roller.

9. Draw-twist apparatus as claimed in claim 1 wherein said thread guide roller is arranged approximately tangent to the linear path of the thread being drawn between feed and draw means with the thread extending from said guide roller in one length which is more strongly tensioned, then passing around both said godet and guide roller and finally from said guide roller in another length which is less strongly tensioned, and said godet is arranged laterally of said guide roller on one side thereof in close proximity to the more strongly tensioned thread length extending from said guide roller.

10. Draw-twist apparatus as claimed in claim 1 wherein said thread drawing means includes an upper feed means and lower draw rolls consisting of said godet in combination with said guide roller, and said thread twisting means is positioned below said lower draw rolls to provide a substantially vertical linear path of thread travel from said upper feed means to said guide roller and again from said guide roller to said twisting means, the thread being wound a number of 5 times around both said godet and said guide roller, and said godet is arranged laterally above said guide roller in close proximity to said first-mentioned substantially vertical linear path of thread travel from said upper feed means to said guide roller.
